(57) **CLAIM**

The ornamental design for a resuscitator, as shown and described.

DESCRIPTION

1. Resuscitator

Figure 1.1 is a left side view of a resuscitator;

Figure 1.2 is a perspective view thereof;

Figure 1.3 is a right side view thereof;

Figure 1.4 is a front view thereof;

Figure 1.5 is a back view thereof;

Figure 1.6 is a top view thereof; and

Figure 1.7 is another perspective view thereof.

The broken lines shown in Figures 1.1-1.7 illustrate portions of the resuscitator that form no part of the claimed design.

1 Claim, 7 Drawing Sheets
